UNITED STATES PATENT OFFICE.

CHARLES EDMUND KELLS, OF NEW ORLEANS, LOUISIANA.

DENTAL APPLIANCE.

1,418,445.

Specification of Letters Patent. Patented June 6, 1922.

Application filed March 17, 1921. Serial No. 453,173.

To all whom it may concern:

Be it known that I, CHARLES EDMUND KELLS, a citizen of the United States, residing at New Orleans, in the parish of Orleans and State of Louisiana, have invented 5 certain new and useful Improvements in Dental Appliances, of which the following is a specification.

The object of this invention is to provide 10 means whereby substances or articles commonly used by dentists may be conveniently supported and readily brought into position to be heated. More particularly my object is to provide means whereby the various substances and articles used in the preparation 15 of novocain may be supported, heated or otherwise treated.

In carrying out my invention I provide a stand comprising a base, an upright or 20 standard, and one or more arms or brackets which extend laterally from the standard and which support test tubes, flasks, or other such devices.

These arms are associated with a heater, 25 such as an electric heater, an alcohol lamp, or Bunsen burner. The base is preferably circular in outline, and the heater is placed eccentrically on the base. The standard is also placed eccentrically on the base and the 30 brackets are of such construction that they may support the test tubes, flasks, etc., in such manner that they may be brought successively or as desired over the burner. It is important that the devices should be kept 35 perfectly clean or free from dust, and in order to do this I provide a cover for them which is preferably transparent and may be an ordinary bell jar of well known form. Provision is made for attaching the cover to 40 the base in such manner that it may be tightly held thereon so that by lifting the cover the base and the entire appliance may be lifted and moved. The cover may be quickly detached from the base when de- 45 sired.

In the accompanying drawings:—

Figure 1 is a perspective view of the apparatus embodying my improvements.

Figure 2 shows a transverse section 50 through the transparent cover with the other parts of the apparatus in plan.

Figure 3 is a bottom view of the apparatus.

Figure 4 is a view, partly in vertical section and partly in elevation of some of the 55 parts.

The apparatus as a whole constitutes what may be called a novocain unit, being provided with means for treating the substances and handling the devices used in the preparation of the solutions. The base A is preferably made of metal and may be supported on rubber feet *a*. It is preferably circular and supports a post or standard B which is preferably placed at one side of the center of the base and may be pivotally connected therewith. The post supports arms or brackets C, D, E and F which in turn support flasks, test tubes, etc. A transparent cover G of the kind commonly called a Bell jar is removably supported on the base and it has a knob or handle *g* as usual. In order to detachably attach the cover to the base the latter is provided with fixed hooks H, H' adapted to engage the rim *g'* of the cover 60 and with a movable hook H² also adapted to engage the rim *g'*. The hook H² is formed on the outer end of an arm *h* pivoted eccentrically at *h'* to the base. By turning the arm *h* to the proper extent, the hook H² may 65 be withdrawn from the cover and the latter removed or by turning the hook to the position shown in Figure 2 the cover may be securely locked to the base. A suitable heater K is supported on the base somewhat to one 70 side of the base center. This heater may be an electric heater, an alcohol lamp or as shown a Bunsen burner supplied by a pipe *k* extending under the base and supported by a bracket *k'*. The pipe *k* is detachably 75 connected with a supply pipe L.

The standard, as before stated, may be pivotally connected with the base, but preferably the brackets or arms C, D, E, F are individually pivoted to the standard. As 80 shown in Figure 4, the standard consists of a rod *b* carrying spacing sleeves *b'* between which the arms are held. The lower end of the rod is threaded as shown to receive a nut *b*². The upper end of the rod *b* is also 85 threaded and receives an adjusting nut *B'*. By tightening the nut, the brackets or arms are held securely in the position to which they are adjusted. By loosening the nut, the arms may be turned to the desired extent. 90 The lower arm or bracket C is preferably provided with posts *c* to center a flask M of special form and called a Ringer flask consisting of a body *m*, a spout *m'*, a filling neck *m*² and a flattened ring *m*³ through 95 which a flat blade may be thrust and thus the flask handled with ease while hot. The arm 100

or bracket C has an opening c' to expose the bottom of the flask to the heater. The arm or bracket D is adapted to support a dissolving tube N and in order that the tube 5 may be covered the bracket D carries a hinged pivoted or removable lid n.

The brackets E and F are adapted to support test tubes O, P or any other devices which it is desired to heat. All of the brackets or arms may be turned to any desired extent in either direction to properly adjust them to bring any one of the elements over the heater and away therefrom.

When in use the cover is of course removed. Ready access may be had to any part of the apparatus and each element may be moved into position for use or out of the way with great facility. When the heat is turned off and the apparatus is not being used, the cover may be quickly applied and securely locked, so that the different parts of the apparatus which it is desired to keep clean are protected from dust and other contamination.

25 I claim as my invention:—

1. A dental apparatus, comprising a base, a heater supported by the base, a post on the base and extending vertically therefrom, brackets carried by the post and projecting laterally therefrom, a cover having a laterally projecting rim at its lower end, and means for detachably locking the cover to the base, comprising hooks fixed to the base and which engage the rim of the cover and 30 a hook carrying arm on the under side of the base and pivoted eccentrically thereon, being adapted to engage the rim of the cover or to become disengaged therefrom, whereby when said arm engages the cover, 35 the base with parts carried thereby may be lifted with the cover.

40 2. A dental apparatus, comprising a base,

a heater supported on the base, a post mounted on the base and extending vertically therefrom, tube supporting brackets supported by the post projecting laterally therefrom, located in different horizontal planes and movable about the axis of the post to bring the outer tube supporting ends of the brackets above the heater, means for holding the brackets firmly in position when adjusted, a cover having a laterally projecting rim at its lower end, and means for locking the cover to the base, comprising hooks fixed to the base which engage the rim of the cover and a hooked arm on the under side of the base and eccentrically pivoted thereto.

3. A dental apparatus comprising a base, a heater supported on the base, a post mounted on the base eccentrically comprising a rod and spacing sleeves, brackets supported by the post projecting laterally therefrom and located in different horizontal planes, and a lid carried by one of said brackets adapted 65 to cover a container supported by said bracket.

4. A dental apparatus comprising a base, a heater carried thereby, a post mounted on the base, a bracket extending laterally from the post and provided with centering posts and having an opening through it to expose the bottom of a flask centered between the posts, another bracket carried by the post for supporting a dissolving tube and which 70 has a hinged lid, and other brackets in horizontal planes above the others which are independently movable about the axis of the post and which are adapted to support test tubes or the like over the heater.

In testimony whereof, I have hereunto subscribed my name.

CHARLES EDMUND KELLS.
